The ornamental design for a hair volumizer, as shown and described.

DESCRIPTION

FIG. 1 is a front, side, top perspective view of a hair volumizer showing my design therefor;

FIG. 2 is a front, side, bottom perspective view thereof;

FIG. 3 is a side elevational view thereof, the opposite side view being a mirror image;

FIG. 4 is a side elevational view thereof in an open position

FIG. 5 is a front elevational view thereof;

FIG. 6 is a rear elevational view thereof;

FIG. 7 is a top plan view of the lower arm of the design with the upper arm removed to reveal the exposed surface of the lower arm; and

FIG. 8 is a bottom plan view of the design;

FIG. 9 is a front elevational view of the lower arm;

FIG. 10 is a rear elevational view of the lower arm;

FIG. 11 is a top plan view of the design;

FIG. 12 is a bottom plan view of the upper arm of design with the lower arm removed;

FIG. 13 is a front elevational view of the upper arm; and,

FIG. 14 is a rear elevational view of the upper arm.

The broken lines shown in the drawings illustrate portions of the hair volumizer that form no part of the claimed design. The upper and lower arms of the design are disclosed specifically for convenience of illustration.
